UNITED STATES PATENT OFFICE.

ADAM H. McALPINE, OF COLUMBUS, OHIO.

BRAKE-BEAM.

SPECIFICATION forming part of Letters Patent No. 289,431, dated December 4, 1883.

Application filed August 24, 1883. (No model.)

To all whom it may concern:

Be it known that I, ADAM H. McALPINE, a citizen of the United States, and a resident of Columbus, in the county of Franklin and State 5 of Ohio, have invented certain new and useful Improvements in Brake-Beams, of which the following is a specification.

In the ordinary construction of railroad-car brakes the shoes which bear against the faces 10 of the wheels have been secured to transverse brake-beams of wood. These wooden brake-beams are heavy, cumbersome, and perishable.

A brake-beam composed of proper metal, 15 disposed in the best form to unite strength and lightness, and so constructed that it can be readily substituted for the wooden beam now in use without changing the castings and other parts of the brake, is a desideratum.

20 My invention relates to such a brake-beam; and it has for its object to provide a substantial, durable, and economical brake-beam for railway-cars, that can be readily substituted for the wooden ones now in general use, as 25 well as to improve the manner of attaching the brake-shoes and the operating-levers and to these ends my invention consists in constructing a brake-beam of wrought-iron or steel, having strengthening-ribs in the direction 30 of the strain, and in attaching the brake-shoes to the beam with adjustable springs, and also-attaching the beam to the brake-levers by means of spring-connections, all as more particularly pointed out hereinafter.

35 In the accompanying drawings, forming part of this specification, in which like letters refer to like parts, Figure 1 is a top view of a brake-beam broken away at one side of the middle. Fig. 2 is a side view of the same. 40 Fig. 3 is an end view of the brake-beam with a brake-shoe attached. Fig. 4 is a sectional view through the beam, showing the head on the brake-rod lever attached; and Fig. 5 is a view of the head detached and partly in section.

45 The brake-beam A is constructed of wrought-iron or steel in such a manner as to be interchangeable with the ordinary wooden beam now in general use, so that the same castings 50 may be utilized, and the beam can thus be substituted for those in ordinary use, thereby securing the benefits of a wrought-iron beam

with very little labor and expense. The beam consists of a central rib, a, having the flanges b b, of equal width, on one side extending 55 throughout its length, and having on the other side the flanges c c, arranged directly opposite the flanges b b, and made tapering from the center toward each end. By this construction the greatest strength is secured with the 60 least amount of metal, and the material is so disposed that the beam is strongest at the point of greatest strain. To the center of the beam is attached the head B, for holding the levers of the brake-rods. The head consists of a 65 main portion, f, having lugs or projections g g, between which the end of the brake-rod lever is secured, and a projecting stem, h, provided with a screw-thread, for the reception of the nut i. The head is secured to the beam 70 by means of the plate d, shaped so as to fit closely upon the flanges b b, and having the screw-bolts e e passing through the rib a. Between the plate d, which may be properly recessed, as shown in Fig. 5, and the nut i is 75 placed a spiral spring, k. By this construction it will be seen that the head is secured to the beam by a spring-connection, and that the tension of the spring may be controlled by adjusting the nut i. Other forms of springs 80 might be used, but the form shown is simple and effective. To the ends of the beam are secured the brake-shoes D D. These may be of any ordinary construction, and may be secured to the beam in the usual manner, or 85 may have a spring-connection between the shoe and the beam, as shown in Fig. 3, so as to allow the face of the shoe to adjust itself to the unequal sides of the wheel, so as to obtain a perfect bearing, and thereby prevent 90 the sliding of the wheels.

Instead of applying the beam-head to the beam, as shown, a spring may be interposed between the brake-rod lever and the head.

It will be seen by the construction set forth 95 the beams may be substituted for the ordinary wooden beams now in use, as no change in the other parts of the brake apparatus will be required, and the spring-connections described allow the beam and its attached shoes to be 100 self-adjusting to the unequal sides of the wheels, whereby the sliding of the wheels is prevented and the consequent wear and tear avoided.

It is evident that the main features of this device may be modified more or less without departing from the spirit of the invention.

I am aware that it is not new to make a 5 brake-beam of wrought-iron, and I do not claim such construction, broadly.

Having now described my invention, what I claim, and desire to secure by Letters Patent, is—

- 10 1. A brake-beam consisting of a bar of rolled metal provided with four flanges, two on each side, those on the same side being of the same width, but of different width from those on the other side, in combination with a brake-lever head attached to the beam at or near the center thereof, and brake-shoes attached at the ends thereof.
- 15 2. A brake-beam consisting of a bar of rolled metal provided with four flanges, two on one side of equal width throughout, and two on the other side tapering toward each end, substantially as described.
- 20

3. The combination, with a brake-beam consisting of a rolled bar of metal provided with four flanges, tapered, as described, of a head 25 for connecting the brake-rod lever, secured to the beam by screw-bolts, substantially as described.

4. The combination, with a brake-beam consisting of a rolled bar of metal provided with 30 four flanges, as described, of a head for the brake-lever, consisting of a plate, *d*, bolted to the beam, and the body *f*, having the projection *h*, carrying a nut, and a spring interposed between the nut and the head, for the purpose 35 set forth.

In testimony whereof I have signed my name to this specification in the presence of two subscribing witnesses.

ADAM H. McALPINE.
